UNITED STATES PATENT OFFICE.

DAVID JOHN SCOTT, OF PLAINFIELD, NEW JERSEY, ASSIGNOR TO ISABELLA SCOTT AND
DAVID J. SCOTT, EXECUTORS OF WALTER SCOTT, DECEASED.

OFFSET PERFECTING-PRESS.

1,273,544.

Specification of Letters Patent. Patented July 23, 1918.

Original application filed April 2, 1915, Serial No 18,639. Divided and this application filed September 29, 1918. Serial No. 122,834.

To all whom it may concern:

Be it known that I, DAVID J. Scott, a citizen of the United States, and a resident of Plainfield, in the county of Union and State of New Jersey, have invented certain new and useful Improvements in Offset Perfecting-Presses, of which the following is a specification.

The present invention relates generally to offset perfecting presses and has more particularly reference to the general arrangement of the printing units in the multi-color press of this type.

The present application is a division of an application Serial No. 18639 filed on April 2, 1915 and has for its main object an arrangement of the printing units and the members composing them whereby both sides of the web are printed in several colors by the offset process and without the omission of elements necessary to produce high class results; and, at the same time, to provide an arrangement of cylinders and other parts whereby all the working parts will be completely accessible.

Another object of this invention is to provide means for conveniently controlling the various instrumentalities that make up the press.

The invention consists of the features of construction, combination of parts and arrangement of elements hereinafter described, the preferred form embodying them being shown in the accompanying drawings. Changes may, however, be made in this particular form without departing from the legitimate and intended scope of this invention.

In the drawing:

E and F represent two impression cylinders located innermost of the machine and forming the impression element of two different units or couples. Associated with the impression cylinder E are form cylinders A and A' and blanket or transfer cylinders C and C'. Associated with the impression cylinder F are two form-carrying cylinders B and B' and blanket or transfer cylinders D and D'. It will be noted that the form-carrying and transfer cylinders of each unit are arranged one above the other and, as here shown, with one form-carrying member at the upper end of the structure and another form-carrying member at the

lower end of the structure. It will also be observed that the units are so grouped that the exposed operating sides formed by the form-carrying and transfer cylinders are located outermost of the machine, and that the impression cylinders E and F are located non-adjacent to the operating side and innermost of the machine. Associated with each form-carrying cylinder is the usual inking device O. When it is desired to employ dampening mechanisms such mechanisms may also be located as shown at N. In the form here shown the dampening mechanisms associated with the form-carrying cylinders A and B are located non-adjacent to the operating side of the machine and intermediate the units of the impression cylinders, while the dampening mechanisms N associated with the form-carrying cylinders A and B are located adjacent the lower end of the operating sides of the units. 37 indicates an anti-smutting device engaging impression cylinder F and located intermediate the two impression cylinders. The object of this anti-smutting device is to prevent the previously printed side of the paper from soiling or smutting the surface of the impression cylinder F.

I indicates a source of supply of paper in web form and K indicates a delivery, here shown conveniently as a flat delivery. The source of supply I and the delivery K are located adjacent to the outermost sides of the machine and are spaced therefrom to provide room for the platforms or gangways G and H. The paper is led from the source of supply I over the guiding rolls X', above the first unit and to a point midway between the two units, thence downwardly between the units and over the guiding roll X², thence to the impression cylinder E, 95 thence across the space between the two units to the impression cylinder F, thence to the guiding rolls X³ and to the delivery.

In order to admit of ready access to the parts, transfer cylinders C C' and D D' are mounted in sliding boxes 54 in a well-known manner so that they may be thrown off the impression and form-carrying cylinders. Suitable means are provided for effecting this movement which need not be described in detail except to say that the manipulation of handles 39 and 37' acts, through the system of levers indicated, to effect the throw-

off of the cylinders. If desired, rods 120 may be employed which connect the throw-off of two transfer cylinders so that two cylinders may be thrown off in unison by the 5 operation of one handle. In the present instance, rod 120 connects two transfer cylinders on opposite sides of the machine.

Similarly, impression cylinders E and F are provided with sliding boxes 54 which 10 are controlled from operating handles 14 and 28 whereby the impression cylinders may be moved inwardly toward each other and away from the coating transfer cylinders. If desired, a rod 26 may connect the 15 handles 14 and 28 so that the two cylinders may be thrown off in unison. Both rods 120 and 26 are provided with a gab hook 36 so that the parts may be disconnected and each cylinder tripped independently of any 20 other cylinder.

In the present instance, the anti-smutting device 37 is mounted on a sliding box 54 of cylinder F so as to be moved bodily with it. It will also be noted that the said 25 anti-smutting device is located between the upper and lower runs of the web passing to and from impression cylinder F, and intermediate the two impression cylinders. These features are disclosed and claimed in a companion application filed Sept. 29, 1916, Serial 30 No. 122,833. The dampening devices are movably mounted with respect to the form-carrying cylinders and may be moved into and out of contact with same by means of 35 lever 34 in a well-known manner.

From the foregoing, it will be seen that the paper in its passage through the machine receives an imprint on one side in several colors and then an imprint on the other side 40 also in several colors, there being a form-carrying cylinder, and a transfer cylinder for each color, and an impression cylinder engaging with a plurality of transfer cylinders.

45 What is claimed, is:

1. A rotary multi-color offset perfecting machine comprising: a plurality of units printing from positive forms on opposite sides of impression receiving material, each 50 unit consisting of two form-carrying and two transfer cylinders and an impression cylinder all of substantially the same diameter, the form-carrying and transfer cylinders being arranged in a vertical column 55 with one form-carrying cylinder uppermost and the other form-carrying cylinder lowermost, and the impression cylinder being arranged intermediate the transfer cylinders and out of line with the other cylinders to 60 afford an exposed operating side for the unit, the units being grouped with their operating sides outermost and with the impression cylinder innermost.

2. A multi-color offset perfecting machine 65 comprising: two side by side units adapted

to print on opposite sides of the impression receiving material, each unit including two form-carrying members, two transfer members and one impression member, the form-carrying members and transfer members of 70 each unit being arranged outermost to form an exposed operating side, and the impression members of the two units being arranged innermost and non-adjacent to the operating sides of the machine, the units 75 being grouped with their operating sides outermost, and means for moving the impression members toward each other and away from the co-operating transfer members. 80

3. A multi-color offset perfecting machine comprising: two side by side units adapted to print on opposite sides of the impression receiving material, each unit including two form-carrying members, two transfer members and one impression member, the form-carrying members and transfer members of each unit being arranged outermost, and the impression members of the two units being arranged innermost of 90 the machine, the form-carrying and transfer members of each unit being located one above the other with one form-carrying member of each unit uppermost and one form-carrying member of each unit lowermost, dampening mechanism for the uppermost form-carrying member of each unit located intermediate the unit, and dampening mechanism for the lowermost form-carrying member of each unit located adjacent 100 to the outer side of the unit. 95

4. A multi-color offset perfecting machine comprising: two side by side units adapted to print on opposite sides of the impression receiving material, each unit including two form-carrying members, two transfer members and one impression member, the form-carrying members and transfer members of each unit being arranged outermost, and the impression members of the two units being arranged innermost of 110 the machine, the form-carrying and transfer members of each unit being located one above the other with one form-carrying member of each unit uppermost and one form-carrying member of each unit lowermost, dampening mechanism for the uppermost form-carrying member of each unit located intermediate the unit, dampening mechanism for the lowermost form-carrying member of each unit located 115 adjacent to the outer side of the unit, and means for moving said dampening mechanisms toward and away from their co-operating form-carrying members. 120

5. A rotary multi-color offset perfecting machine comprising: two side by side units adapted to print on opposite sides of the impression receiving material, each unit including two form-carrying cylinders, two transfer cylinders and one impression cylinder 125 130

der, the form-carrying cylinders and transfer cylinders of each unit being arranged outermost and the impression cylinders of the two units being arranged innermost of the machine, the form-carrying and transfer cylinders of each unit being located one above the other with one form-carrying cylinder of each unit uppermost and one form-carrying cylinder of each unit lowermost, and means for moving the impression

cylinders inwardly of the machine toward each other and away from the coöperating transfer cylinders.

Signed at Plainfield, in the county of Union and State of New Jersey, this 27 day 15 of September, A. D. 1916.

DAVID JOHN SCOTT.
